ATTORNEY

UNITED STATES PATENT OFFICE.

RICHARD A. PORTER, OF PATCHOGUE, NEW YORK.

DESIGN FOR A BADGE.

No. 87,817.

Specification for Design.

Patented Feb. 13, 1906.

Application filed August 9, 1905. Serial No. 273,484. Term of patent 3½ years.

To all whom it may concern:

Be it known that I, RICHARD A. PORTER, a citizen of the United States, residing at Patchogue, in the county of Suffolk and State of New York, have invented a new, original, and ornamental Design for a Badge, of which the following is a specification, reference being had to the accompanying drawing, forming part thereof.

The figure is a plan view of a badge, showing my new design.

I claim—

The ornamental design for a badge, as shown.

RICHARD A. PORTER.
